SUPPORTING MEANS FOR REFRIGERATING APPARATUS

Harold A. Greenwald, Detroit, Mich., assignor to Thomas C. Whitehead, Detroit, Mich.

Application May 28, 1931, Serial No. 540,736

10 Claims. (Cl. 62—116)

This invention relates generally to supporting means for refrigerating apparatus such as the portable apparatus of the package unit type illustrated in my pending application, Serial No. 440,556 filed March 31, 1930, now Patent No. 1,898,438, patented February 21, 1933, and consists of certain novel features of construction, combinations and arrangements of parts that will be hereinafter more fully described and particularly pointed out in the appended claims.

In the accompanying drawings:

Figure 1 is a section through the refrigerator with parts broken away;

Figure 2 is a section on the line 2—2 of Figure 1;

Figure 3 is a sectional plan of a portion of a refrigerator showing one of the slides attached thereto;

Figure 4 is a section on the line 4—4 of Figure 3;

Figure 5 is a perspective view of one of the plates;

Figure 6 is a perspective view of one of the slides.

Referring now to the drawings, A is a refrigerator cabinet of substantially rectangular configuration provided at its upper end with a transversely extending vertical partition 1 having forwardly and rearwardly extending stepped portions 2 and 3 respectively secured to the front and rear walls 4 and 5 of the cabinet and dividing the latter into compartments B and C respectively. As shown, the compartment B is accessible through an opening 6 in the front wall of the cabinet and is adapted to receive food, while the compartment C is accessible through an opening 7 in the partition 1 and is adapted to receive refrigerating apparatus D. 6' are openings for air in the front wall of the cabinet and 7' and 7'' respectively are passages at the top of the cabinet establishing communication between the openings 6' and compartment C whereby air from the atmosphere may be conducted to and from the compartment C.

Preferably the refrigerating apparatus D is a portable unit of the compressor expansion type with the refrigerant high and low sides E and F thereof in a common horizontal plane upon opposite sides of an upright panel G. Thus the high side of the apparatus including the compressor 8 and associated parts such as the motor 9, fan 10 and condenser 11 may be within the compartment C; the panel G may abut the forward face of the upright partition 1 and close the opening 7 therein, and the low side F of the apparatus in-

cluding the cooling element 12 may be within the food compartment B. As shown, the compressor 8, condenser 11 and motor 9 are mounted upon a base H that is rigid with the panel G, while the cooling element 12 is mounted upon 60 and projects forwardly from the panel G.

In the present instance the base H of the unit is guided to and from the proper position within the compartment C and is supported therein by means of slides 15 and 16 which are pivoted at 65 their forward ends upon the upright side walls 17 and 18 respectively of the opening 7 and are movable vertically for a limited distance in plates 19 and 20 respectively secured to uprights 21 and 22 respectively of the cabinet. As shown, each 70 slide has a horizontal portion 24, a vertical portion 25 and a flange portion 26. Preferably the vertical portion 25 is at one longitudinal edge of the horizontal portion and extends a short distance beyond the rear end thereof, while the 75 flange portion 26 projects laterally from the upper edge of the vertical portion 25 adjacent the rear end thereof. The horizontal portion 24 serves as a seat for the base H, the projected ends 27 of the upright portions 25 are received 80 in slots 29 and 30 in the plates 19 and 20, and the flanges 26 overlap the base H and serve to retain the same on the horizontal portions 24 of the slots.

Thus with this construction the base H with 85 the high side E of the refrigerating apparatus thereon may be readily moved through the opening 7 and slid longitudinally of the sides 15 and 16 until the panel G abuts the partition 1. Inasmuch as the slides 15 and 16 are pivoted at 90 their forward ends and have a limited vertical movement at their rear ends, the high side E of the refrigerating unit may be engaged with the slides even though the base H is not exactly at right angles to the partition 1 and the opening 7 95 may be effectively closed by the panel G even though the panel should not be at a true right angle to the base H, as the play afforded by the slides 15 and 16 will permit the panel G to adapt itself properly to the front face of the partition 1. Moreover, the weight of the parts on the slides 100 will automatically maintain the rear ends of the slides down and thus will cause the panel G to be held firmly against the partition 1. In other words, the center of gravity of the entire machine unit is on the opposite side of the slide pivot points from the panel, therefore with the unit in place gravity maintains the panel tightly against the vertical machine opening. If desired, a single clamp 31 may be used to secure the panel 110

G against the partition 1. Thus the unit may be easily and quickly moved to and from operative position in the cabinet. The opening 7 will be closed even though inaccuracies in assembly of 5 the base and panel occur and it is not necessary to use a number of securing means to retain the parts in such operative position.

What I claim as my invention is:

1. In combination, a refrigerator cabinet having an upright part provided with an opening through which portable refrigerating apparatus may be inserted, and a support for such apparatus including an element permanently mounted in said cabinet independently of said refrigerating apparatus for pivotal movement relative to said part. 10

2. In combination, a refrigerator cabinet having an upright portion provided with an opening through which the high side of refrigerating apparatus may be inserted, and a support for such apparatus including a slide pivoted upon said upright portion. 20

3. In combination, a refrigerator cabinet having an upright partition provided with an opening through which the compressor of refrigerating apparatus may be inserted, and a support for such compressor including slides pivoted at their forward ends upon the side walls of said opening. 25

4. In combination, a refrigerator cabinet having an upright partition provided with an opening through which a portion of refrigerating apparatus may be inserted, and a support for such apparatus including slides pivotally engaging the partition at spaced points thereof, and means in 30 rear of said partition for limiting the pivotal movement of said slides.

5. In combination, a refrigerator cabinet having an upright partition provided with an opening through which a compressor of a refrigerating apparatus may be inserted, and a support for such compressor including slides pivoted upon the side walls of the opening and extending rearwardly with respect to said partition, and stationary means in rear of said partition for limiting the 40 pivotal movement of said slides.

6. In combination, a refrigerator cabinet having an upright partition provided with an opening through which refrigerating apparatus may be inserted and having an upright member in 45

rear of said partition, an element carried by the upright member and having a slot therein, and a slide for refrigerating apparatus pivoted at its rear end movable in the slot in said element. 80

7. In combination, a refrigerator cabinet having an upright partition provided with an opening through which a base of a portable refrigerating apparatus may be inserted and which is adapted to be closed by a panel carried by said base, and a support for said base including means independent of said base permanently carried by and movable relative to said partition, whereby the panel may close the opening. 85

8. In combination, a refrigerator cabinet having an upright part provided with an opening through which the high side of a portable refrigerating apparatus may be inserted, and a support for such apparatus including slides pivotally mounted for movement in rear of said part. 90

9. In combination, a refrigerator cabinet having a food compartment and a machine compartment, a portable refrigerating apparatus including a low side adapted to be received in said food compartment and a high side adapted to be received in said machine compartment, and a support for said high side including means secured to a fixed wall of the machine compartment and being arranged for pivotal movement within said machine compartment. 95

10. In combination, a refrigerator cabinet having a food compartment and a machine compartment and being provided with an opening leading to the food compartment, a unitary refrigerating apparatus including a refrigerant condensing element adapted to be received in said machine compartment, a refrigerant evaporating element adapted to be received in said food compartment, and a slab of insulating material disposed between said elements, and a support for said condensing element comprising means secured to a stationary 100 wall of the machine compartment and being arranged for pivotal movement in said machine compartment whereby said slab of insulating material seals said food compartment from said machine compartment by the weight of said condensing element, said unitary refrigerating apparatus being insertable and removable into and from said cabinet through said opening. 110

G against the partition 1. Thus the unit may be easily and quickly moved to and from operative position in the cabinet. The opening 7 will be closed even though inaccuracies in assembly of 5 the base and panel occur and it is not necessary to use a number of securing means to retain the parts in such operative position.

What I claim as my invention is:

1. In combination, a refrigerator cabinet having an upright part provided with an opening through which portable refrigerating apparatus may be inserted, and a support for such apparatus including an element permanently mounted in said cabinet independently of said refrigerating apparatus for pivotal movement relative to said part. 10

2. In combination, a refrigerator cabinet having an upright portion provided with an opening through which the high side of refrigerating apparatus may be inserted, and a support for such apparatus including a slide pivoted upon said upright portion. 20

3. In combination, a refrigerator cabinet having an upright partition provided with an opening through which the compressor of refrigerating apparatus may be inserted, and a support for such compressor including slides pivoted at their forward ends upon the side walls of said opening. 25

4. In combination, a refrigerator cabinet having an upright partition provided with an opening through which a portion of refrigerating apparatus may be inserted, and a support for such apparatus including slides pivotally engaging the partition at spaced points thereof, and means in 30 rear of said partition for limiting the pivotal movement of said slides.

5. In combination, a refrigerator cabinet having an upright partition provided with an opening through which a compressor of a refrigerating 40 apparatus may be inserted, and a support for such compressor including slides pivoted upon the side walls of the opening and extending rearwardly with respect to said partition, and stationary means in rear of said partition for limiting the 45 pivotal movement of said slides.

6. In combination, a refrigerator cabinet having an upright partition provided with an opening through which refrigerating apparatus may be inserted and having an upright member in 50

rear of said partition, an element carried by the upright member and having a slot therein, and a slide for refrigerating apparatus pivoted at its rear end movable in the slot in said element. 80

7. In combination, a refrigerator cabinet having an upright partition provided with an opening through which a base of a portable refrigerating apparatus may be inserted and which is adapted to be closed by a panel carried by said base, and a support for said base including means independent of said base permanently carried by and movable relative to said partition, whereby the panel may close the opening. 85

8. In combination, a refrigerator cabinet having an upright part provided with an opening through which the high side of a portable refrigerating apparatus may be inserted, and a support for such apparatus including slides pivotally mounted for movement in rear of said part. 90

9. In combination, a refrigerator cabinet having a food compartment and a machine compartment, a portable refrigerating apparatus including a low side adapted to be received in said food compartment and a high side adapted to be received in said machine compartment, and a support for said high side including means secured to a fixed wall of the machine compartment and being arranged for pivotal movement within said machine compartment. 95

10. In combination, a refrigerator cabinet having a food compartment and a machine compartment and being provided with an opening leading to the food compartment, a unitary refrigerating apparatus including a refrigerant condensing element adapted to be received in said machine compartment, a refrigerant evaporating element adapted to be received in said food compartment, and a slab of insulating material disposed between said elements, and a support for said condensing element comprising means secured to a stationary wall of the machine compartment and being arranged for pivotal movement in said machine compartment whereby said slab of insulating material seals said food compartment from said machine compartment by the weight of said condensing element, said unitary refrigerating apparatus being insertable and removable into and from said cabinet through said opening. 105
